UNITED STATES PATENT OFFICE.

ISAAC A. ROMMER, OF NEW YORK, N. Y.

DESIGN FOR A DOLL-SWING.

49,161.

Specification for Design.

Patented June 6, 1916.

Application filed December 20, 1915. Serial No. 67,942. Term of patent 7 years.

To all whom it may concern:

Be it known that I, ISAAC A. ROMMER, a citizen of the United States, residing in the borough of Manhattan, county of Kings, and State of New York, have invented a new, original, and ornamental Design for Doll-Swings, of which the following is a specification, reference being had to the accompanying drawing, forming part thereof.

Figure 1 is a front view, and Fig. 2 is a side view of a doll swing showing my new design.

I claim:

The ornamental design for a doll swing as shown.

Signed at New York in the county of Kings and State of New York this 17 day of December, A. D. 1915.

ISAAC A. ROMMER.

Witnesses:

C. S. ASHLEY,
L. H. BROWN.
